(57) **CLAIM**

The ornamental design for a table, as shown and described.

DESCRIPTION

FIG. 1 is a perspective view of a table showing my new design;

FIG. 2 is a front view thereof, the rear view, the right-side view and the left-side view being symmetrically identical;

FIG. 3 is a top view thereof;

FIG. 4 is a bottom view thereof;

FIG. 5 is a sectional view thereof through the Section 5-5 of FIG. 2; and,

FIG. 6 is an enlarged fragmentary view showing the top right corner of the table in greater detail.

The broken line depiction of environmental structure is provided for illustrative purposes only and forms no part of the claimed design.
